(57) **CLAIM**

We claim the ornamental design for a modular power supply container, as shown and described.

DESCRIPTION

FIG. 1 is a perspective view of a modular power supply container, showing our new design;

FIG. 2 is a front view thereof, the back view being a mirror image thereof;

FIG. 3 is a top view thereof; and,

FIG. 4 is a side view thereof, the opposite side being a mirror image thereof.

The broken line portion of the figure drawings is included to show portions of the article that forms no part of the claimed design.

1 Claim, 4 Drawing Sheets

FIG. 1

FIG.2

FIG.3

FIG.4
